UNITED STATES PATENT OFFICE.

WALTER J. KREIDER, OF NEAR DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed July 2, 1924. Serial No. 723,689.

This invention relates to cash registers, and more particularly to the mechanism for controlling the opening of the cash drawers.

The principal object of this invention is 5 the provision of mechanism for controlling the release of cash drawers from a plurality of banks of keys.

A specific object is the provision of mechanism for releasing the same drawers from 10 a plurality of banks of keys.

With these and incidental objects in view, the invention consists of certain novel features of construction and combinations of parts, the essential elements of which are 15 set forth in appended claims and a preferred form of embodiment of which is hereinafter described with reference to the drawings which accompany and form part of this specification.

20 Of said figures:

Fig. 1 is a section through the machine, in which the present invention is embodied, taken just to the right of one of the banks of control keys.

25 Fig. 2 is a detail perspective view of a portion of the mechanism for selecting the cash drawer to be released.

Fig. 3 is a fragmentary rear elevation of 30 the mechanism shown in Fig. 2, together with two of the cash drawers, and the means for unlatching them.

Fig. 4 is a detail perspective view of the mechanism for unlatching the selected cash drawer.

35 Fig. 5 is a longitudinal section of the selecting shaft shown in Fig. 4.

General description.

This invention is shown embodied in a 40 cash register of the type shown and described in the patent to Frederick L. Fuller No. 1,394,256. In machines of this type it is usually customary to provide three banks of control keys. Such machines can 45 also be equipped with any number of cash drawers from one to nine, one drawer being provided for each clerk using the machine. In the previous machines of this type the release of the cash drawers was controlled 50 by a single bank of keys, but this machine has been designed so that each cash drawer may be released by a key in each of the three control banks. It will be evident that 55 this drawer control mechanism can be constructed to operate in connection with two,

three or more banks of control keys. It will be evident, from the following description of the invention, that the construction shown herein is of a flexible nature, and it is not intended to confine the invention to 60 the particular form shown herein, nor its use to the particular type of cash register disclosed.

Keyboard and differential mechanism.

The three banks of control keys, which are 65 all of the keyboard with which the present invention is concerned, are identically the same, and are shown in detail and described in the above referred to Fuller patent. The 70 showing and the description thereof in this application therefore will be as much simplified as possible. Each bank contains nine keys 30 (Fig. 1), which are slidably mounted in a key frame 31, supported at its upper 75 and lower ends by rods 32 and 33. These keys are adapted to be held in their depressed position during the operation of the machine, and restored to their undepressed position at the end of such operation in a 80 manner which is very well known, and the description of which is accordingly omitted here.

The differential mechanism for the release banks is old and well known and only a 85 very brief description thereof will be included in this application. A latch member 34 is pivotally supported by an arm 35 and a bell crank lever 36, which are in turn carried by a differentially movable member 37. This member is pivoted on a stud 38 and is driven by an invariably moved segment 39, also pivoted on the stud 38. The segment 39, as is well known, is given its invariable movement by means of a link 40, a Y-shaped member 41 and a pair of cams 42 and 43, which are fast on a shaft 44. This shaft is the main drive shaft of the machine and receives one complete rotation on every operation thereof, thereby causing the Y-shaped member 41 to rock first clockwise and then counter-clockwise about its pivot. On the clockwise movement of the Y-shaped member 41, the segment 39 and the differentially movable member 37 will be rocked clockwise until the forward end of the bell crank lever 36 comes into contact with the inner end of whichever one of the keys 30 has been depressed. When this occurs, the latch member 34 will be disconnected from 100 105 110

a shoulder on the invariably moved segment 39 and the differentially movable member 37 will be stopped in a position corresponding to the key depressed. If no key in a bank 5 has been depressed, the latch will be broken or moved into unlatching position by means of a zero stop pawl 45, the operation of which is very well known and which is shown in the copending application of B. M. 10 Shipley No. 576,924, filed July 20, 1922. The bell crank lever 36 is connected by a slot and pin connection to a member, shown broken away, also pivoted on the stud 38 which is in the same plane as the zero stop pawl 45. 15 When the invariably moved segment 39 is rocked counter-clockwise to its normal position, a surface 46 thereof will strike a pin 47 on the differentially movable member 37 and return this member to its normal 20 position. Pivoted to the member 37 is a beam 48, which at its opposite end is bifurcated and cooperates with a pin 49 carried by a link 50. The link 50 is pivoted at its upper end to a segment 51, which is 25 adapted to position both the corresponding indicators and the desired totalizer in a manner which is described in the above referred to patent. At its lower end, the link is pivoted to an arm 52 loose on a rod 53 30 supported by the machine side frames. Secured to the arm 52 is a segment gear 54, the teeth of which mesh with teeth formed on the forward end of a rack 55. The forward end of this rack is slidably supported 35 in a cross member 56, also supported by the machine frames. The rear end of the rack 55 carries teeth 57 which mesh with a gear 58 loose on a shaft 59 (Figs. 1, 2 and 3). This shaft is rotatably mounted in two 40 brackets 60 and 61 which rest on the base of the machine. The Y-shaped member 41 carries a roller 62 which, when the Y-shaped member receives its clockwise movement, will contact with the lower edge of 45 the beam 48 and position this beam and the link 50 differentially, in accordance with the position in which the latch of the differential mechanism was broken under control of the depressed key. The differential movement of the link 50 will be 50 transmitted through the arm 52, segment 54 and rack 55 to the gear 58, which is appropriate to the particular bank operated, and this gear will therefore be rotated in a 55 clockwise direction a distance corresponding to the key depressed. Each of the gears 58 is connected by means of a hub 63 (Fig. 2) to an arm 64 which lies in the same plane as a pin 65 carried by an arm 66 60 fast on the shaft 59. It is, therefore, apparent that when the gear 58 corresponding to the key bank operated is given its clockwise movement, the shaft 59 will be carried in a clockwise direction to an extent 65 corresponding to the key depressed, but the

arms 64 for the other banks of control keys will not be moved.

Drawer mechanism.

The drawer mechanism of the present 70 machine is of conventional design in most respects, and it is not believed that a specific description of the mechanism is essential to an understanding of the invention.

As shown in this application, the machine 75 is provided with nine cash drawers. Fig. 3 showing the top and bottom drawers only. Each of the cash drawers 77 is slidably mounted in an opening in the base of the machine. On the back of each of the drawers a bracket 78 is bolted, to which is pivoted a drawer latch 79 which has a shoulder 80 engaging a hardened plate laid in a bar 81 extending laterally across the rear of the machine, and supported by vertically extending members 82. There is one 80 of these bars for each drawer. The latch 79 is held in its latching position by means of a spring 83 stretched between a projection on the latch and a pin on the bracket 78. When the drawer is unlatched in a manner which will be presently described, it is moved forwardly out of the drawer cabinet under the influence of two springs 84, the construction and function of which 85 are old and well known.

The cash drawer to be released is selected by the key depressed in any of the three control banks. The machine is so constructed that only one key may be depressed 100 in the three banks. No matter in which bank the depressed key may be, the shaft 59 (Figs. 2 and 3) will be rotated differentially in accordance therewith in the manner previously described. Fast on this 105 shaft is a spiral gear 85, which meshes with a spiral pinion 86 (Fig. 4) fast on a short vertical shaft 87. At its lower end, the shaft 87 carries a member 88, the front and back of which are flattened, and which is 110 adapted to be inserted into a corresponding opening in a cylindrical member 89 carried on the upper end of a shaft 90 as shown more clearly in Fig. 5. It can be seen that due to the construction of these parts a 115 rotary movement of the spiral pinion 86 will be transferred to the shaft 90, and also a vertical movement of the shaft 90 and the member 89 can be effected without raising the spiral pinion 86. At its lower end the shaft 90 rests on a projecting lug 91 extending upwardly from the base of the drawer cabinet. A torsion spring 94 is wound about the shaft 90, and is anchored at one 120 end to a collar 92 which is secured to the shaft, and at its other end to a portion 93 of the frame. This spring constantly tends to rotate the shaft 90 in a counter-clockwise direction, as viewed in Fig. 4, in order, 125 through the spiral gear 85 and shaft 59, to 130

- keep the pins 65 on arms 66 constantly in engagement with the arms 64. It can be seen from the above description that when the shaft 59 is rotated differentially by the differential mechanism appropriate to one of the three control banks of keys, the shaft 90 will also be rotated differentially to a like extent against the tension of the spring 94.
- 10 Fast on the shaft 90 are a plurality of lugs, or fingers, 95, which are differentially and spirally disposed about the periphery of the shaft 90, one opposite each of the cash drawers. Thus, if the "9" key in any 15 one of the three banks is depressed, and through the differential mechanism the shaft 90 is rotated to its "9" position, the lug 95 appropriate to the lower, or ninth, cash drawer will be moved into position to 20 cooperate with this drawer. Pivotaly mounted on the frame 81 is a lever 100, the movement of which is limited by a pin 101 which projects through an opening in said lever. The lever extends laterally of the 25 machine and normally lies just above the latching arm 79 for each cash drawer. It is evident that when the left hand end (Fig. 3) of the lever 100 is raised, the right hand end will be lowered and therefore the 30 latch arm 79 will be pushed downwardly far enough to disengage its shoulder 80 from the plate in bar 81 and thereby permit the springs 84 to force the drawer forwardly to its open position. The means for 35 rocking the lever 100 will now be described.
- It can be seen in Fig. 4 that the member 89, which is carried on the upper end of the shaft 90, has a horizontally extending channel 102 cut therein. Fast on a shaft 40 103 is a U-shaped member 104 which carries two pins 105 projecting into the channel 102. Fast on the shaft 103 is an arm 106, the free end of which rests on the left hand end of a lever 107 pivoted on a stud 108 of the frame. The opposite end of the lever 107 carries a roller 109, which cooperates 45 with the periphery of a cam 110 fast on a shaft 111. This shaft is the main printer drive shaft, shown in the above mentioned patent and there numbered 242, Figs. 50 and 51, and receives a complete clockwise rotation (Fig. 4) upon every operation of the machine. When this operation takes place, the cam 110 will rock the lever 107 clockwise, which will in turn rock the arm 55 106, shaft 103 and U-shaped member 104 also clockwise, thereby raising the member 89 and shaft 90 upwardly, the cam 110 will then permit the parts to return to their normal positions, as shown in Fig. 4. Upon 60 the upward movement of the shaft 90 the lug 95, which had previously been positioned under control of the keys, will co-operate with its appropriate lever 100 and rock this lever, thereby rocking the latch 65 arm 79 and releasing the particular drawer selected.
- While the form of mechanism herein shown and described is admirably adapted to fulfill the objects primarily stated, it is 70 to be understood that it is not intended to confine the invention to the one form of embodiment herein disclosed, for it is susceptible of embodiment in various forms, all coming within the scope of the claims 75 which follow.
- What is claimed is:
1. In a cash register, the combination of a plurality of cash drawers, a finger shaft the position of which determines which of 80 said drawers will be released, a transverse shaft adapted to drive said finger shaft, a plurality of arms fast on said shaft, studs projecting laterally from said arms, a plurality of members loose on said shaft one 85 for each of said arms, gears secured to said members, and racks one for each of said gears for operating the finger shaft to determine which of said drawers is to be released. 89
2. In a drawer selecting mechanism, the combination of a shaft for controlling the selection of drawers, a plurality of arms fast thereon, and means for driving said arms to different extents in order to position said shaft. 95
3. In a drawer selecting mechanism, the combination of a shaft for controlling the selection of drawers, a plurality of arms fast thereon, pins projecting laterally from said arms, and means cooperating with said pins for driving said arms and positioning said shaft to select the drawer to be operated. 100
- In testimony whereof I affix my signature.

WALTER J. KREIDER.
